US0D1068815S

(12) **United States Design Patent** (10) **Patent No.:** **US D1,068,815 S**
(45) **Date of Patent:** **** Apr. 1, 2025**

(54) **DISPLAY SCREEN WITH A GRAPHICAL USER INTERFACE**

(71) Applicant: **Sanofi (China) Investment Co., Ltd., Shanghai (CN)**

(72) Inventor: **Dong Wang**, Paris (FR)

(73) Assignee: **SANOFI CHINA INVESTMENT CO. Ltd., Shanghai (CN)**

(**) Term: **15 Years**

(21) Appl. No.: **29/914,891**

(22) Filed: **Oct. 23, 2023**

(30) **Foreign Application Priority Data**

Apr. 24, 2023 (CN) 202330233212.4

(51) **LOC (15) Cl.** **14-04**

CLAIM

The ornamental design for a display screen with a graphical user interface, as shown and described.

DESCRIPTION

The FIGURE is a front view of a display screen with a graphical user interface showing my new design.

The outermost broken line illustrates a display screen that forms no part of the claimed design.

1 Claim, 1 Drawing Sheet
